Primary Examiner — Michael A Maharajh(74) *Attorney, Agent, or Firm* — Peter A. Koziol; Assouline & Berlowe, P.A.(57) **CLAIM**

The ornamental design for a pelvic harness attachment, as shown and described.

DESCRIPTION

FIG. 1 is a front view of a pelvic harness attachment showing my new design;

FIG. 2 is a rear view thereof;

FIG. 3 is a side view thereof;

FIG. 4 is a top view thereof;

FIG. 5 is a bottom view thereof;

FIG. 6 is a front perspective view thereof; and,

FIG. 7 is a rear perspective view thereof.

The broken lines shown in the drawings are for the purpose of illustrating portions of the pelvic harness attachment, which form no part of the claimed design.

1 Claim, 6 Drawing Sheets(56)
